(57) **CLAIM**

The ornamental design for a construction element, as shown and described.

DESCRIPTION

FIG. 1 shows a left side view of the construction element;

FIG. 2 shows a right side view thereof;

FIG. 3 shows a front view thereof;

FIG. 4 shows a rear view thereof;

FIG. 5 shows a top plan view thereof;

FIG. 6 shows a bottom plan view thereof, wherein the broken lines form no part of the claimed design; and,

FIG. 7 shows a perspective front view thereof.
